Inventor:

Frieda Schmidtke

UNITED STATES PATENT OFFICE.

FRIEDA SCHMIDTKE, OF BERLIN, GERMANY.

LAMP.

Application filed September 16, 1927, Serial No. 219,975, and in Great Britain August 23, 1927.

My invention relates to lamps particularly such as used in hand lanterns, carriage lanterns and the like, and consists in combining the lamp with a petrol lighter arranged so as to allow of lighting the lamp without opening the casing or other protector. The object of this arrangement is to facilitate the lighting of the lamp in stormy weather and to eliminate the risk incurred when lamps are lit with matches and the like in the presence of straw or other easily inflammable substances.

In the accompanying drawings the invention is illustrated in connection with a burner such as used for hand lanterns,

Fig. 1 representing a view of the lighter and the burner,

Fig. 2 a view at right angles to Fig. 1, and

Fig. 3 a top view of the arrangement.

The perforated plate *b* which supports the globe or other flame protector *t* of the lantern and through which the lamp burner *x* projects, carries on its underside a small petrol container *r* having a filling aperture which is accessible from the top of the plate *b* and which is normally closed by a screw stopper *s*. A wick tube *a* proceeding from the container *r* is arranged so as to hold the exposed end of the wick in a position enabling the flame to be utilized for lighting the burner *x*. Opposite the wick tube *a* an abrasive wheel *u* is arranged on a shaft *d* which is mounted in the brackets *c* on the plate *b*. There is also on the shaft a pinion *e* which meshes with a gear wheel *f* arranged under the plate *b*. The wheel *f* is mounted on a shaft *h* which is accessible from the outside of the lantern and fitted with a milled wheel *g* whereby the shafts and the wheel *u* can be turned. The shaft *h* is held in a sleeve *k* and is shouldered for engagement with a screw cap *i* which is fitted on the end of the sleeve to prevent axial displacement of the shaft. A flint *v* is arranged in a tube

y under the wheel *u* and is pressed against the latter by means of a spring in the usual manner so as to produce, when the abrasive wheel is turned, the sparks whereby the flame of the wick tube *a* is kindled.

Normally the wick tube *a* is covered by a cap *o* which is carried, through the medium of an arm *n* by a disc *m* arranged loosely on the shaft *d*. The disc *m* is formed with crown teeth for engagement with similar teeth on a clutch member *p* which is slidably feathered on the shaft *d* and controlled by a spring *z*. When the wheel *g* is turned for operating the abrasive wheel, the disc *m* is turned by the clutch member *p* so as to raise the cap *o* from the wick tube. However, the clutch teeth are inclined so as to allow the member *p* to slip after the cap, whose movement is limited, has been fully opened. When the burner *x* has been lit the wheel *g* is turned backwards for applying the cap *o* to the wick tube so as to extinguish the lighter flame. In this movement the clutch members are positively engaged and no slipping can take place.

I claim:

The combination in a lighting device for lamps especially lanterns, of a lamp burner and a secondary burner lighted by means of a pyrophoric sparking device consisting of a metallic container of spirit, a wick tube *a*, a cap to close the mouth of said tube fastened by means of an arm to a disc *m*, turning loosely on a shaft *d*, mounted in brackets *c*, a clutch member *p* slidably feathered on said shaft *d* and controlled by a spring *z*, an abrasive wheel *u*, a flint *v* pressed against said wheel and a pinion *e* fixed on shaft *d*, said pinion meshing with a gear wheel *f* mounted on the shaft *h*, a milled wheel *g* to turn said shafts, all substantially as described.

In testimony whereof I affix my signature.

FRIEDA SCHMIDTKE.
